UNITED STATES PATENT OFFICE.

EMIL A. KANN, OF NEW YORK, N. Y.

BELT.

1,247,688.

Specification of Letters Patent. Patented Nov. 27, 1917.

Application filed July 11, 1917. Serial No. 179,892.

To all whom it may concern:

Be it known that I, EMIL A. KANN, a citizen of the United States, and a resident of New York, in the county of New York and State of New York, have made a certain new and useful Improvement in Belts, of which the following is a specification.

This improvement relates to belts and more particularly to the class of belts used by those in the army and navy and is exceptionally well adapted for use by the wounded. To that end the belt is formed of two main parts each having a portion formed of elastic webbing, with the ends slit and separated, and gores of non-elastic material purposely made full and inserted between said slit ends whereby the belt is made to conform to the shape of the user.

The invention consists in the details of construction hereinafter described and then definitely pointed out in the claim at the end hereof.

In the drawing accompanying and forming part hereof:

Figure 1 is a perspective view of my belt. Fig. 2 is a section of the same through the line 2—2 of Fig. 1.

Fig. 3 is a blank showing how the elastic webbing is cut and its ends separated or spread apart ready for the insertion of a gore.

Referring now to the details of the drawings by numerals: 1 and 2 designate the two main parts of my belt which are preferably connected at the rear by the usual or any desired lacing 3, as illustrated in Fig. 1. Each of the parts 1 and 2 is preferably formed of a back piece 5 made of any ordinary fabric having stays 8 and 9 if desired. The front halves of the parts 1 and 2 are formed in the main of elastic webbing 10 and 11. In the process of manufacture the

elastic webbing is cut as illustrated in Fig. 3 and its ends are separated to make room for a gore 15 of non-elastic material. As indicated in Fig. 2, this gore is preferably made of two thicknesses of material sewed to the edges of the elastic webbing, and it is purposely made full to cause the belt to assume the curved position indicated in Fig. 50 2. The clasps 16 and 18 are located in the usual strips of fabric 20 and 21 securely sewed to the ends of the elastic webbing and the end of the gore 15; these parts also being caused to assume a slightly curved part 55 owing to the fullness of the gore 15.

I am aware that belts of this character have before been employed but I believe I am the first to provide a belt wherein the main portion of the front of the belt is 60 formed of elastic webbing with its ends cut and separated and between which separated ends are secured gores purposely made full in order that the belt at the front is caused to assume a curved shape to conform to the 65 shape of the wearer.

What I claim as my invention is:

In a device of the character described, the combination of two main parts detachably connected together at the front and each 70 comprising a member formed of elastic webbing and extending from the rear to the front of the abdomen and slit to form separated ends, and a non-elastic gore inserted between said separated ends and made full 75 to cause the members to assume a curved shape, substantially as described.

In testimony whereof I affix my signature in presence of two witnesses.

EMIL A. KANN.

Witnesses:

FRED'K W. DECKER,
JOHN J. POLLARD.
